(57) **CLAIM**

The ornamental design for an ultra high density fiber enclosure, as shown and described.

DESCRIPTION

FIG. 1 is a front elevational view of an ultra high density fiber enclosure showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, rear and right side perspective view thereof;

FIG. 8 is a bottom, front and left side perspective view thereof;

FIG. 9 is an enlarged view of portion 9 in FIG. 3;

FIG. 10 is an enlarged view of portion 10 in FIG. 6;

FIG. 11 is an enlarged view of portion 11 in FIG. 7;

FIG. 12 is an enlarged view of portion 12 in FIG. 7;

FIG. 13 is an enlarged view of portion 13 in FIG. 8; and,

FIG. 14 is an enlarged view of portion 14 in FIG. 8.

The broken lines in the drawings illustrate portions of the ultra high density fiber enclosure which form no part of the claimed design.
